BALING PRESS

William L. Steinhauer, Columbus, Ga., assignor
to Cen-Tennial Cotton Gin Company, Colum-
bus, Ga., a corporation of Georgia

Application April 8, 1939, Serial No. 266,809

9 Claims. (Cl. 100—19)

This invention relates to new and useful im-
provements in presses for baling cotton or like
material.

In the past, considerable difficulty has been ex-
perienced in baling presses caused by the ex-
pansive urge of the cotton when being com-
pressed. This expansion is so great at times that
it puts an undue load onto the baling door and
lock mechanisms on the baling doors. The ex-
pansion outwardly in a bale of cotton is very
slight, being about one-half inch, but the pres-
sure exerted is about one-half of the total pres-
sure applied to the plungers. After the cotton
lint is set by the trumper in the bottom boxes
and top baling compartment underneath the dogs
and pressure is applied packing the bale, the
sidewise pressure of the cotton becomes great
enough to do damage to the frame and panels of
the baling compartment.

Accordingly, the principal object of my in-
vention is to overcome the above defined defect
in prior baling press constructions and I ac-
complish this object by providing a set of doors
using a rigid frame, which is composed of the
baling door channels and the door locking clamps,
using, however, a floating panel mounted on
springs, the springs being strong enough to with-
stand the original tramping load, but are re-
silient enough to allow the baling doors to ex-
pand slightly when the full pressure of the ram,
or rams, is applied.

In using a cushion type door with more than
enough expansion room than will ever be re-
quired for the expansive sidewise urge of the cot-
ton, the actual pressure on the frame members
can be ascertained and the frame members can
be built considerably lighter than if it were neces-
sary to try and hold this expansion. Thus, a
further object of the present invention is to con-
struct a press of lighter weight and at a lower
cost than has been done heretofore.

The invention also resides in certain novel fea-
tures of construction, combination and arrange-
ment of the various parts and in certain modes
of operation, all of which will be readily under-
stood and appreciated by those skilled in the art
upon reference to the accompanying drawings
in connection with the detailed description ap-
pearing hereinafter.

In the drawings wherein the same reference
characters have been designated the same parts
in all views,

Figure 1 is a front elevational view illustrating
a two-story double box cotton press incorporat-
ing my invention.

Figure 2 is an enlarged view of one of the doors
disclosed in Figure 1.

Figure 3 is a plan view of one of the press
boxes.

Figure 4 is a section taken on line 4—4 of Fig-
ure 2.

Figure 5 is a section taken on the line 5—5 of
Figure 2.

Figure 6 is a detail section through a corner
of the box illustrating the function of the clamp- 10
ing members.

The present invention is illustrated as applied
to the press boxes of a two-story up-ranking
double box hydraulic press, the general arrange- 15
ment of which is indicated more or less conven-
tionally, but which is sufficient to illustrate the
use and adaptation of the present invention. The
specific form of press is shown for illustrative
purposes only, the invention not being limited in
its application to any particular type of press. 20

In the form of press illustrated, 1 designates
the support having vertical columns 2 and 3 and
upper cross members 4 and 5 constituting the
main framework of the press.

Cross member 4 supports the trumper mech- 25
anism shown in Figure 1, but which forms no part
of the present invention, although designated as
6 for purposes of convenience and reference.

Suitably mounted in the frame member is
column 7. The duplicate press boxes 8 and 9 30
are swingably supported on this column 7, the
press boxes being connected by the substantially
circular platform 10.

The press also includes movable bottoms or
follow blocks 12 in each of the press boxes which 35
are adapted to be engaged by a ram to force the
movable bottoms upwardly so that the material
in the press is carried into the baling portion at
the upper end of each of the boxes and firmly
compressed therein against the head block 13 40
carried by the upper frame 5.

The press itself is of conventional type. The
trumper 6 feeds the cotton into the box as shown
in Figure 1. While this is going on, the ram 11
is acting upon the follow block 12 in the other 45
press box 8 for compressing the cotton upwardly
toward the head block 13. The follower block
12 forms the bottom of the press box. The trumper
will fill the box with cotton substantially to
the top. The follower block 12, under the in-
fluence of ram 11 compresses the cotton into the
upper end of the box which is formed by the door
members which will be referred to later on.

The press boxes 8 and 9 are identical in con-
struction and at this point, particular attention 55

is called to the fact that as a result of the rotation of boxes 8 and 9 about column 7, in the position of the press as seen in Figure 1, box 9 discloses the front wall whereas box 8 discloses 5 the rear wall. Since the two boxes are of the same construction, a description of front wall 14 of box 9 and rear wall 15 of box 8 will serve as a description of the front and rear walls of both boxes. Thus, the numerals designating the 10 various parts of front wall 14 of box 9 will designate like parts of front wall of box 8, and the numerals designating the various parts of rear wall 15 of box 8 will designate like parts of the rear wall of box 9.

15 As seen in Figure 1, the upper part of wall 14 is disclosed as the non-lock side baling door 16. The upper part of wall 15 forms the locking side baling door 17. The door 17 broadly comprises panels 18 mounted on channel bars 19 20, 21 and 22. The door 16 broadly comprises panels 18 mounted on channel bars 23, 24, 25 and 26. The specific manner of mounting the panels on the channel bars to obtain a floating action for the panels comprises the inventive 25 concept of the present invention and will be described in detail later on.

The doors 16 and 17, as usual, carry the dogs 27 which extend into the press boxes. Also conventional, as shown on the locking door 17, is 30 the lock wheel 28, door lock toggles 29 and worm wheel 30.

A detail description of the manner of mounting the panels on the channel members will now be given. The channel members 23 and 24 are 35 connected by spaced bolts 31, 31 herein shown as two in number, and the channel members 25 and 26 are similarly connected by bolts 32, 32. The panels 18 are welded or otherwise joined to channel members 33. A relatively short channel member 34, of sufficient length to bridge the bolts 32 (see Figures 2 and 5), is disposed between the lower channel members 25 and 26. This channel member 34 is located between the bolts and the channel member 33. A plurality 40 of springs 35 are disposed between the channel members 33 and 34. There is a cup 35a suitably secured to the outer face of the channel member 33 for each spring, and this cup serves to locate and support the spring. These springs 35 45 bear against the channel members 34 as an abutment and normally tend to move the panels 18 inwardly and away from the channel members 25 and 26. There is a similar channel member 34 between the channel members 23 and 24 which 50 bears against the bolts 31, and also similar springs 35 bearing against the upper channel member 33.

Attached at each end of the channel members 33, 33 are bolts 36. These bolts may be welded 60 or otherwise secured to the channel members 33. The two upper bolts 36 lie between the channel members 23, and 24, and the two lower bolts lie between the channel members 25 and 26. Extending between the channel members 23 and 65 24 is a plate 37 which is welded or otherwise secured to the channel members. There is also a straddle plate 38 welded to the channel members 23 and 24. These plates 37 and 38 are provided with openings through which the bolts 70 36 pass. These openings are dimensioned so as to form a support for the bolts 36. The bolts 36 between the channel members 25 and 26 pass through plates similar to the plates 37 and the straddle plate 38, and are supported and guided 75 therein. Each bolt carries a collar 39 which

is secured to the shaft by a suitable pin 39a. A spring 40 abuts against the collar and against the straddle plate. These springs normally force the plates to the right as viewed in Figure 4, until the collars are brought into contact with 5 the cross plates 37. Thus it is that the panel members 18 form a rigid panel assembly which is yieldably supported by the door frame and this panel assembly extends substantially from one side of the press box to the other side thereof as 10 shown in Figure 3.

Referring to Figure 3, it is seen that the panels extend in between the side walls 44 and 45. These side walls are in the form of doors hinged at the bottom for outward movement to permit 15 removal of the bale from the press. As further shown in Figure 3, both the front and rear doors carry a pair of brackets or clamps 41 for co-operation with the side doors to clamp the doors in position and also serving to permit the side 20 doors to give slightly when the bale is being compressed. Each bracket or clamp 41 comprises a flat base portion 42 which is welded or otherwise secured to the floating panel assembly adjacent the upper edge of the door, and a curved 25 portion 43 which lies outside of the door members 44 and 45. Thus, in the normal inward position of the floating panels, the brackets 41 operate on side doors 44 and 45 to force them to their closed position. However, during the 30 outward movement of the panel assembly resulting from the compression of the cotton within the press, the brackets will also move outwardly, and as a result of the curved portions of the brackets, the side doors will open slightly, 35 thereby relieving the full pressure on said side doors. This action is illustrated by the dotted lines in Figure 6.

The construction described herein eliminates any possibility of warping or straining the press. 40 When the ram 11 actuates the follow block 12 into the upper part of the press which is defined by the doors hereinbefore referred to, the pressure becomes quite great, that is to say, the lateral pressure of the cotton being compressed. However, instead of having a rigid set of doors to receive this pressure with consequent warping and straining, with the present improved construction, the panels of the front and rear walls will move outwardly against the pressure of the 45 springs thus taking up any lateral pressure caused by the cotton. It is obvious that the amount of outward expansion can be readily ascertained and the springs made sufficiently strong to accommodate the maximum expansion. 55

As disclosed in Figures 4 and 5, the panels are so mounted with respect to the transversely extending channel members as to leave a space between the inner edges of the channel members and the outer face of the panels. This allows 60 sufficient distance for the panels to move outwardly as a result of the outward expansion of the cotton within the press. It is also seen that the height of the channel irons 33 is such as to allow said irons to project into the space between 65 the channel members without interfering with said channel members.

Since the outward expansion of the cotton can be determined, the space between the panels and the inner edges of the channels can be made 70 sufficiently large to accommodate the maximum expansion of the cotton without contact between the panels and the channel members. Thus, since the channel members do not receive any load from the expanding cotton, the channel 75

members may be made of a much lighter construction than heretofore used resulting in lower costs for the press.

Although the present disclosure shows the floating panels in the front and rear doors only, it is obvious that the present invention contemplates the use of floating panels in the end doors if so desired.

Thus it will be seen that the construction herein shown and described is well adapted to accomplish the objects of the present invention. It will be understood, however, that the invention may be embodied otherwise than here shown and that in the form illustrated, certain changes in the construction may be made. Therefore, I do not wish to be limited precisely to the construction herein shown except as may be required by the appended claims considered with reference to the prior art.

Having thus described the invention, what is claimed is:

1. In a baling press, a press box comprising a plurality of doors, at least one of said doors formed of panels, a plurality of reinforcing members extending transversely of the panels and spaced therefrom, and yieldable means mounting said panels to the reinforcing members for permitting outward movement of the panels upon outward pressure within the press box.

2. In a baling press, a press box comprising a plurality of doors, at least one of said doors formed of panels, a plurality of reinforcing members extending transversely of the panels and spaced therefrom, means for mounting said panels on said reinforcing members, and a series of springs mounted between the panels and the reinforcing members for permitting limited outward movement of the panels upon outward pressure against said panels.

3. In a baling press, a press box comprising a plurality of doors, a pair of oppositely disposed doors formed of movable panels, reinforcing members extending transversely of the panels and spaced therefrom, means for mounting said panels on said reinforcing members, and yieldable means mounted between the panels and the reinforcing members urging the panels inwardly but permitting outward movement of said panels upon outward pressure within the press box.

4. In a baling press, a press box comprising a plurality of doors, a pair of oppositely disposed doors formed of movable panels, reinforcing members extending transversely of the panels and spaced therefrom, means for mounting said panels on said reinforcing members, yieldable means mounted between the panels and the reinforcing members urging the panels inwardly but permitting outward movement, and means at the edges of said oppositely disposed doors for cooperating with the edges of the other pair of

doors for clamping said latter pair of doors in closed position.

5. In a baling press, a press box comprising a plurality of doors, a pair of oppositely disposed doors formed of movable panels, reinforcing members extending transversely of the panels and spaced therefrom, means for yieldably mounting said panels on said reinforcing members, the other pair of doors hingedly mounted at their lower ends, and means on said panels adjacent their upper edge for cooperating with the edges of the hinged doors for clamping said latter pair of doors in closed position.

6. In a baling press, a press box comprising a plurality of doors, a pair of oppositely disposed doors formed of movable panels, reinforcing members extending transversely of the panels and spaced therefrom, means for yieldably mounting said panels on said reinforcing members, the other pair of doors hingedly mounted at their lower ends, and clamping members joined to said panels adjacent their upper edge, said clamping members having angularly disposed portions for cooperating with the hinged doors for holding said doors in closed position.

7. In a press, a press box comprising a plurality of doors, at least one of said doors formed of outwardly movable panels, a pair of reinforcing members extending transversely of the panels and spaced therefrom, bolts connecting the reinforcing members, a bar bridging said bolts between the bolts and panels, and resilient means interposed between the bar and panels for urging the panels inwardly against any outward pressure within the box.

8. In a baling press for cotton, a press box comprising a plurality of doors, at least one of said doors formed of outwardly movable panels, a bar transverse of said panels and connecting said panels, a pair of reinforcing members extending transversely of the panels and spaced therefrom, bolts connecting the reinforcing members, a channel bar bridging said bolts between the bolts and said panel connecting bar and spring means between the channel bar and the connecting bar for urging the connecting bar inwardly.

9. In a cotton baling press, a press box comprising a plurality of doors, at least one of said doors formed of outwardly movable panels, a bar connecting said panels, a pair of reinforcing members extending transversely of the panels and spaced therefrom, a straddle plate bridging the outer edges of the reinforcing members and substantially parallel to the plane of the panels, a bolt between the reinforcing members and connected to said connecting bar and passing through the straddle plate and spring means surrounding the bolt between the connecting bar and the straddle plate for urging the connecting bar inwardly.

WILLIAM L. STEINHAUER.
